Primary Examiner — Philip S Hyder*Assistant Examiner* — Darlington Ly(74) *Attorney, Agent, or Firm* — Global IP Counselors, LLP(57) **CLAIM**

The ornamental design for a front grill for an automobile, as shown and described.

DESCRIPTION

FIG. 1 is a front elevation view of a front grill for an automobile in accordance with my new design;

FIG. 2 is a rear elevation view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a front-right side perspective view thereof; and,
 FIG. 8 is a cross-sectional view thereof, as taken along the section line 8-8 in FIG. 1.

The broken line showing of the front grill is for purpose of illustrating environmental structure and forms no part of the claimed design.

The cross sectional view of FIG. 8 is provided to clarify the exact contour or configuration of the exterior surface of the front finisher, and no attempt is made to illustrate features of internal construction.
